(57) **CLAIM**

The ornamental design for a breakaway lanyard closure device, as shown and described herein.

DESCRIPTION

FIG. 1 is a perspective view of a breakaway lanyard closure device showing my new design;

FIG. 2 is a top plan view;

FIG. 3 is an end elevational view, the opposite end being the same;

FIG. 4 is a side elevational view, the opposite side being the same; and,

FIG. 5 is a bottom plan view.

The broken line portions of the disclosure are for illustrative purposes only and form no part of the claimed design.
